CLAIM

The ornamental design for a camera as shown and described.

DESCRIPTION

FIG. 1 is a front view of a camera;
FIG. 2 is a rear view of the camera shown in FIG. 1;
FIG. 3 is a front perspective view of the camera shown in FIG. 1;
FIG. 4 is a side perspective view of the camera shown in FIG. 1;
FIG. 5 is a second side perspective view of the camera shown in FIG. 1;
FIG. 6 is a top view of the camera shown in FIG. 1; and,
FIG. 7 is a bottom view of the camera shown in FIG. 1.
The broken lines in the figures illustrate the portions of the camera that form no part of the claimed design.
